UNITED STATES PATENT OFFICE.

IRA C. BUCKMINSTER, OF BEVERLY, MASSACHUSETTS, ASSIGNOR TO UNITED SHOE MACHINERY CORPORATION, OF PATERSON, NEW JERSEY, A CORPORATION OF NEW JERSEY.

COATING APPARATUS.

Application filed August 16, 1920. Serial No. 403,711.

My invention relates to apparatus for the application of fluid coatings to such work as parts of shoes, it being especially designed for the cementing of the lower portions of the uppers of shoes of the tennis or sneaker type preparatory to laying the foxing strips which assist in securing the soles to the uppers.

An object of the invention is to provide a simple arrangement by which a suitable supply of the coating fluid to the applying member is assured during the entire operation of such member over the area to be coated. In the attainment of this object, I associate with the applying member an initial source of supply, as a container in which it is immersed, and further continue the supply by other or auxiliary means separate from the applying member, as from a receptacle, effective after the withdrawal of the applying member from the container. By such an organization, the applying member, which may be a brush, is charged with the fluid in preparation for the application to the work, and, as the coating continues, the additional delivery makes up for the exhaustion of the initial supply. As illustrated, a brush or other coating member is movable into and out of the contents of a tank, bringing therefrom cement which is transferred to the work. With the brush may move a receptacle receiving cement while in the tank, and delivering to the brush when raised to continue its supply.

Another object of the invention is to bring about the coating of the work surface with a considerable body of the fluid. When such a coating substance as cement is merely rubbed or brushed upon the work, there is a tendency for the applying member to retain too much of the fluid upon itself, while if the cement is laid upon a surface without the rubbing action, its cohesion causes it to draw together and thus reduce unduly the width of the coated area. To overcome these difficulties, I furnish, as a feature of the invention, novel means for accomplishing successively both the rubbing and laying-on effects. The first gives a retentive coating which holds well the succeeding application put on more thickly and without rubbing, the adhesion of the second coating to the first exceeding the cohesion of

its own particles. To this end, there is associated with a member having a fluid-applying surface, means for maintaining a body of the fluid adjacent to such surface. The applying surface causes the rubbing-in of the fluid, while the fluid body deposits the thickened coating thereon. This body should be upon the side of the applying surface toward which the work moves, and may be retained by a member spaced from the applying member, I having illustrated a plate adjacent to an applying brush and having a projection extending below the brush.

A further object of the invention is to more accurately gage or define the area to be coated. For this purpose there is a member co-operating with the applying member and with the work, and this co-operating member is prevented from smearing or unevenly distributing the coating fluid upon the work by means which removes said fluid from the member. When the applying member and gage member are both immersed in the coating fluid, the gage tends to carry with it a portion of the fluid, which, by its contact with the work will destroy the evenness of the line which it is the function of the gage to produce. The present invention avoids this by a fluid-removing means, which acts upon the gage when it is withdrawn from the fluid. To accomplish this removal, I have disclosed herein a member with which the gage member contacts, there being between said members relative movement during their contact. Thereby the fluid is wiped from the gage member. Preferably, a spring acts upon the gage to effect this cleaning movement, it being torsioned during the travel of the applying member and gage with reference to the fluid-supplying means, as the tank in which they are immersed, and thereafter released to produce the cleaning movement.

For illustration of an organization for accomplishing the above and other objects, reference may be had to the accompanying drawings, in which—

Fig. 1 is a perspective view of one embodiment of my invention, with parts broken away;

Fig. 2 is a similar view, taken from another angle and with the cover removed

and the gage-disk separated from its supporting post;

Fig. 3 illustrates in perspective the applying member, with the auxiliary delivery spout and portions of the cleaning mechanism;

Fig. 4 is a vertical transverse section through the apparatus; and

Fig. 5 is an enlarged section detail on the line 5 of Fig. 4.

The coating fluid, as cement, it being assumed that my invention is to be utilized in the preparation of shoe parts to receive their foxing strips, is held in a body of suitable depth in such a container as a tank 10, supported upon a column 12. Pivoted at 14, between opposite walls of the tank and near one extremity, is a carrier arm 16 held normally in a lowered position toward the bottom of the tank by a helical spring 18 co-operating with the arm and with the tank wall. The pivot of the arm 16 has fixed upon it another arm 20 joined by a vertical rod 22 with a treadle, which is not illustrated. Cement is brought from the supply in the tank, when the arm 16 is raised by the depression of the treadle, by an applying member, preferably furnished by a brush 24 having an inclined body 25 clamped by screws 26 in a groove in the extremity of the arm opposite its pivotal support. When not in active use, the brush is held by the spring 18 below the surface of the fluid, and is thus prevented from becoming hardened by evaporation. The ends of the bristles or other fibers forming the brush are inclined similarly to the body portion, giving an applying surface 28. The contour of this is such as to approach the mean curvature transversely of the foxing area about the entire periphery of a shoe upper, so that, with the yield of the fibers, the brush will readily conform to the entire surface to be coated when the work is passed along the applying surface in a horizontal direction. Spaced from one side of the brush, preferably that which the work leaves in its advance, is a wall 30 having its outer edge inclined similarly to the applying surface. At the lower edge of the wall is a flange 31 extending across the space and beneath the brush. The wall and flange form, with the brush, a pocket holding a body of cement over which the work is passed after it has traversed the applying surface 28. Thus, after the cement has been rubbed into the work by the brush, travel across the pocket will tend to deposit a thicker coating, which, because of the previous preparation of the surface, will not draw together, but will retain its uniform distribution. Extending horizontally outwardly from the applying surface of the brush is a work-rest, here shown as consisting of separated rods or rolls 32, 32, mounted upon a yoke 34, which

is pivoted at 36 upon a sliding block 38. The block 38 is arranged to move in ways 40, formed upon the outer wall of the tank and lying at an angle generally corresponding to that of the applying surface 28. The block and work-rest may be adjusted in the ways by means of a screw 42 threaded into the block and having a collar 44 entering a groove between the ways. By turning this screw, the relation of the rest to the upper edge of the applying surface may be varied, correspondingly altering the width of the area which is to be coated during the horizontal travel of the work along the brush. The pivotal mounting of the rest permits it to be moved from the working position, illustrated in Figs. 1 and 5 of the drawings, to one in which it is wholly clear of the top of the tank, as shown in dotted lines in Fig. 5, to provide for a substantially hermetical closure of the latter. This closure may be furnished by a cover 46, having an upwardly projecting portion 47 to receive within it certain portions of the apparatus to be later described, this cover being bolted to the top of the tank at 48. To give access to the applying member during use of the apparatus, the cover has a movable section 50, hinged at 52 upon one side of the tank. A spring 54 associated with the hinge exerts its tension to force the vertical edge of the section 50 against a corresponding edge of the main cover 46 when the section is brought into co-operation with the tank, thus increasing the efficiency of the closure.

As to the organization thus far described, it will be seen that when the arm 16 is raised by the treadle, a quantity of cement is brought by the brush 24 into a suitable position for application to work moved over the rest 32. This quantity of cement, however, does not provide properly for the coating of the entire foxing area. I therefore arrange for an auxiliary supply, preferably through the instrumentality of a cup or receptacle 56, which may be threaded upon the upper extremity of a post or upright 58 rising from the surface of the arm 16 at the rear of the brush. In the bottom of the cup is an opening registering with a passage 60 through the post, this passage terminating in a delivery nozzle 62, which is preferably narrowed vertically and is of such a width as to deliver across the entire upper surface of the brush and to the pocket furnished by the plate 30. When the arm 16 is lowered, as appears in Fig. 4 of the drawings, the cup 56 is beneath the surface of the body of cement in the tank and becomes filled. When the arm is raised to the position of Figs. 1 and 2, or as shown in dotted lines in Fig. 4, the cement contained in the cup flows gradually through the nozzle 62 upon the brush, this continuing the supply as it is distributed over the work.

To form a well-defined line at the upper edge of the coated area so that the applied cement will not project unevenly beyond the foxing and mar the upper, it is desirable to employ a gage contacting with the work in proximity to the upper edge of the brush. This gage is most effectively mounted with the brush upon the arm 16, and consequently is immersed with it when the arm is lowered and becomes covered with cement. This accumulation of cement upon the gage would interfere with its function in determining clearly the edge of the foxing area, and I have therefore provided means for removing the cement from the gage prior to the application of the work to the brush. The gage is shown as in the form of a concave disk having a frusto-conical body 64 overhanging and surrounding the nozzle 62, and supported upon a horizontal flange at the lower extremity of a sleeve 66 arranged to turn about the post 58. Between the sleeve 66 and the post is an intermediate sleeve 68, also rotatable and presently to be further described. A nut 70 clamps the gage-disk upon the sleeve-flange, and a collar 72 limits the upward movement of the sleeves, this collar being fixed to the post between the upper ends of the sleeves and the cup 56. About the bottom of the frusto-conical body is a horizontal flange 74, which extends over the upper side of the brush and into close proximity with the upper edge of the applying surface 28. The edge of this flange, when properly cleaned, resting against the work as it is moved over the brush, furnishes a barrier to the upward passage of cement over the work, and thus maintains the uniformity of this boundary of the foxing area. Arranged to co-operate with the upper surface of the gage-disk is a contact member 76, preferably formed from some such yieldable material as felt. This member has an inclined edge 78 arranged to bear against the conical surface of the gage, and a horizontal end 80 for engagement with the flange 74. The member or block 76 may be mounted in a holder 82 having a vertical stem 83 arranged to slide in a socket formed in the cover 46. A spring 84, surrounding the stem, acts to hold the contact block normally downward, but yields when the gage-disk strikes said block upon the elevation of the arm 16, to furnish effective cleaning engagement between the surfaces 78 and 80 and the opposed surfaces of the disk. Relative movement between the gage and block is provided for to clean the cement from the former, preferably by moving the gage beneath the block. The inner sleeve 68, surrounding the post 58, carries upon a lower flange 86 an upwardly extending spring detent 88, which engages the teeth of a circular ratchet 90 formed under-

neath the flange of the sleeve 66. The flange 86 also carries an arm 92, acted upon by a spring 94 to turn the arm, sleeve and parts carried thereby in a clockwise direction (Fig. 2) until the arm contacts with a stop-projection 96 rising from the brush arm 16. To the outer extremity of the arm 92 is secured a segment 98, in the upper face of which is a depression 100. This depression may be engaged by a latching pawl 102, pivoted upon an arm 104 arranged to turn about the post 58 below the nozzle 62. The arm 104 is joined by a link 106 to the long arm of a bell-crank lever 108 fulcrumed upon a depending portion 110 of the brush arm 16. The shorter arm of the bell-crank lever is united by a link 112 to some such fixed point as the wall of the tank. When the arm 16 is lowered by the treadle to immerse the brush in the cement, the connection of the bell-crank lever 108 to the tank, as the fulcrum point of the lever is carried downwardly, turns said bell-crank in a clockwise direction (Fig. 2) until the pawl 102 engages the depression 100 of the arm 92. As the brush arm is caused to rise, the connection to the tank swings the bell-crank in the opposite direction. This moves the arm 104 in an anti-clockwise direction (Fig. 2), carrying the arm 92 with it, because of the engagement between the pawl and depression. At this time the detent 88 moves idly over the teeth of the ratchet 90, their inclination being such as to permit this. Rotation of the arms 92 and 104 continues until the brush arm has nearly reached its operating point, the spring 94 of the arm 92 being put under tension. The upper surface of the gage-disk 64 and its flange now rest against the cleaning block 78, and at this time an upturned end 114 of the pawl 102 strikes a contact portion 116 depending from the inner wall of the cover 46. This raises the end of the pawl from the depression 100, releasing the arm 92. Said arm is thereupon rotated clockwise by the spring 94, and the detent 88, by its engagement with the ratchet-teeth 90, also turns the gage-disk 64, moving the upper conical and horizontal surfaces beneath the faces 78 and 80 of the cleaning block. By this rubbing action between the block and gage, the cement is removed from the latter, so that when the operator presents the work to the applying brush, the gage is freed from any excess of the coating fluid. To prevent reverse rotation of the gage-disk from taking place under the influence of the mere frictional engagement of the detent 88, thus destroying the continuity of the cleaning effect, there may contact with the under side of the flange 74 a brake member, in the form of a spring 118 fixed to the projection 96 of the arm 16. This exerts suf-

ficient friction upon the disk to hold it against rotation in the direction opposite to that caused by the positive engagement of the detent and ratchet teeth.

In using the apparatus, the cover section 50 of the tank being thrown back, said tank supplied with cement to a suitable depth and the rests 32 being turned over the tank into co-operation with the brush and adjusted to give the proper effective brush width, the operator places a lasted shoe, indicated at S in Fig. 5 of the drawings, upon the rest. Then, pressing down the treadle to raise the brush, he moves the shoe horizontally over the brush with the flange 74 of the gage contacting with the upper. The brush during its immersion in the cement became initially charged, thus furnishing a supply for the work at the beginning of its travel, this being supplemented by the flow from the cup 56 through the nozzle 62, which passes upon the upper edge of the brush beneath the gage and runs over the applying surface. The gage, before contact of the work with it, has been cleaned of the adhering cement in which it was immersed, by its rotation beneath the block 76 under the influence of the spring 94, tensioned during the descent of the arm upon the preceding operation, and released when the arm rises for the operation under consideration. The coating of the upper is completed, at least for a single operation, by a complete horizontal rotation of the shoe in contact with the brush, cement being received both from said brush and from the pocket at its side. Thereupon the treadle may be released and depressed to again supply the brush and cup, and the operation repeated.

Having described my invention, what I claim as new and desire to secure by Letters Patent of the United States is:—

1. In a fluid-applying apparatus, an applying member, means for initially supplying fluid to the member, and means arranged to hold fluid separate from the applying member and to deliver thereto as an auxiliary to the initial applying means.

2. In a fluid-applying apparatus, a fluid container, an applying member movable into and out of the fluid in the container, and means arranged to hold a body of fluid out of contact with the applying member and to deliver it to said applying member when it is out of the fluid in the container.

3. In a fluid-applying apparatus, a fluid container, an applying member movable into and out of the fluid in the container, and holding means movable with the applying member into the fluid and including a passage for supplying fluid to the applying member.

4. In a fluid-applying apparatus, a fluid container, an applying member movable into and out of the fluid in the container, and a

receptacle independent of the applying member, movable with said applying member and delivering thereto.

5. In a coating apparatus, a tank, a brush movable into and out of the contents of the tank, and a receptacle arranged to move with the brush and to discharge its contents thereon when out of the tank.

6. In a coating apparatus, a tank, an arm pivoted in proximity thereto, a brush mounted upon the arm and movable thereby in relation to the tank, and a receptacle mounted upon the arm and having an outlet delivering to the brush.

7. In a fluid-applying apparatus, applying means, fluid-supplying means therefor, a gage member co-operating with the work, and a cleaning member, one of said members being movable relatively to the other in a fixed path.

8. In a fluid-applying apparatus, applying means operating over a definite area of the work, fluid-supplying means therefor, a member defining the edge of the area, and means for cleaning the member.

9. In a fluid-applying apparatus, movable applying means, fluid-supplying means therefor, a member co-operating with the work, and means made effective in the movement of the applying means for removing fluid from the member.

10. In a coating apparatus, a fluid container, an applying member, a gage member co-operating with the applying member and with the work, means arranged to immerse the members in the fluid, and means for removing fluid from the gage member.

11. In a coating apparatus, a fluid container, an applying member, a gage member co-operating with the applying member and with the work, means arranged to move the members into and out of the fluid in the container, and cleaning means with which the gage member contacts upon its withdrawal from the fluid.

12. In a fluid-applying apparatus, applying means, a member co-operating therewith and with the work, means arranged to supply fluid to the applying means, the member also receiving fluid, and means for moving the member to remove the fluid therefrom.

13. In a fluid-applying apparatus, an applying member, a work-gage co-operating therewith, means arranged to supply fluid to the applying member, a gage also receiving fluid, a member with which the gage contacts, and means for moving the gage along said member to remove the fluid.

14. In a coating apparatus, a fluid container, an applying member, a gage member co-operating with the applying member and with the work, means arranged to move the members into and out of the fluid in the container, a cleaning member with which the gage member contacts upon its withdrawal

from the fluid, and means for moving the gage member in contact with the cleaning member.

15. In a coating apparatus, a fluid-applying member, a gage member, means for supplying fluid to the applying member, a cleaning member for the gage member, and means arranged to move the applying member and gage member between the supplying means and cleaning means.

16. In a coating apparatus, a fluid-applying member, a gage member, means for supplying fluid to the applying member, a cleaning member for the gage member, means arranged to move the applying member and gage member between the supplying means and cleaning means, and means for moving the gage member and cleaning member relatively in contact with each other.

17. In a coating apparatus, a fluid-applying member, a movable gage member, means for supplying fluid to the applying member, a cleaning member for the gage member, means arranged to move the applying member and gage member between the supplying means and cleaning means, a spring acting upon the gage member, and means for tensioning the spring during the movement of the members in one direction, the tension being utilized to carry the gage member along the cleaning member upon movement in the other direction.

18. In a coating apparatus, a fluid-applying member, a movable gage member, means for supplying fluid to the applying member, a cleaning member for the gage member, means arranged to move the applying member and gage member between the supplying means and cleaning means, a spring acting upon the gage member, means including ratchet mechanism for tensioning the spring during the movement of the members in one direction, the tension being utilized to carry the gage member along the cleaning member upon the completion of the movement, and yieldable means resisting the movement of the gage member.

19. In a coating apparatus, a fluid-applying member, a movable gage member, means for supplying fluid to the applying member, a cleaning member for the gage member, means arranged to move the applying member and gage member between the supplying means and cleaning means, a spring acting upon the gage member, means for tensioning the spring during the movement of the members from co-operation with the supplying means, and means for releasing the tension after contact of the gage member with the cleaning member.

20. In a coating apparatus, a tank, a carrier movable into and out of the contents of the tank, a brush mounted upon the carrier, a gage movable upon the carrier adja-

cent to the brush, a spring connected to the gage and carrier, means for tensioning the spring in the movement of the carrier, a latch for the gage, a cleaning member with which the gage contacts when it is out of the contents of the tank, and means for releasing the latch during contact between the gage and cleaning means.

21. In a coating apparatus, a tank, a carrier movable in the tank, a brush mounted upon the carrier, a gage movable upon the carrier adjacent to the brush, a spring connected to the gage and carrier, connections to the tank for tensioning the spring, a latch for the spring, and contact members for engagement with the gage and latch.

22. In a coating apparatus, a tank, a carrier movable in the tank, a brush mounted upon the carrier, a gage movable upon the carrier adjacent to the brush, a spring connected to the gage and carrier, connections to the tank for tensioning the spring during movement of the carrier, a latch for the spring, and contact members for engagement with the gage and latch when said gage approaches the operating position.

23. In a coating apparatus, a tank, a carrier movable in the tank, a brush mounted upon the carrier, a gage movable upon the carrier adjacent to the brush, a spring connected to the gage and carrier, connections between the gage and tank for tensioning the spring, said connections including a latch and ratchet means, and contact members for engagement with the gage and latch.

24. In a coating apparatus, a tank, an applying member arranged to move in said tank, a cover for the tank movable to give access to the applying member and to close the tank, and a work-rest mounted upon the tank to move into cooperation with the applying member and into the path of the cover and out of co-operation with the applying member to free the tank for the closing of the cover.

25. In a coating apparatus, a tank, an applying member arranged to move in said tank, a cover for the tank movable to give access to the applying member and to close the tank, a slide mounted upon the tank, means arranged to vary the position of the slide, and a work-rest pivoted upon the slide to move into and out of the path of the cover and co-operating with the applying member.

26. In a fluid-applying apparatus, a member having a fluid-applying surface, and means for maintaining a body of the fluid adjacent to the applying surface for direct contact with the work independent of the action of the applying member on said work.

27. In a fluid-applying apparatus, a member having a fluid-applying surface arranged for movement of the work over it, and means extending along adjacent sides of the applying surface and co-operating therewith

115

120

125

130

to maintain a body of the fluid at the side of the applying surface toward which the work moves in its co-operation with said applying surface.

28. In a fluid-applying apparatus, a fluid container, an applying member movable into and out of the fluid in the container, and means co-operating with the applying member to bring therewith from the container a body of fluid for contact with the work as an auxiliary to that carried by the fluid-applying surface.

29. In a coating apparatus, a brush having an applying surface, a member spaced from the brush and extending into proximi-

ty with the applying surface, and means arranged to supply a coating fluid to the brush surface and to the space.

30. In a coating apparatus, a brush having an applying surface, a plate spaced from a side of the brush and extending into proximity with the applying surface, said plate having a portion extending below the brush, and means arranged to supply a coating fluid to the applying surface and to the space formed between the brush and the plate and its projection. 20 25

In testimony whereof I have signed my name to this specification.

IR A C. BUCKMINSTER.
